(57) **CLAIM**

The ornamental design for an enclosure, as shown and described.

DESCRIPTION

FIG. 1 is an upper perspective of an enclosure, showing our new design;

FIG. 2 is a front elevation view thereof;

FIG. 3 is a rear elevation thereof;

FIG. 4 is a left side elevation view thereof;

FIG. 5 is a right side elevation view thereof;

FIG. 6 is a top view thereof;

FIG. 7 is a bottom view thereof;

FIG. 8 is an upper perspective view thereof with the front cover removed;

FIG. 9 is a front elevation view thereof with the front cover removed; and,

FIG. 10 is an enlarged perspective view of area "10" shown in FIG. 8.

The front cover is shown removed in FIGS. 8-10 for convenience of illustration only.

The portions of the enclosure shown in broken lines form no part of the claimed design.

1 Claim, 10 Drawing Sheets
